AIR CONDITIONING APPARATUS

Joseph W. Kreuttner, North Tarrytown, N. Y., assignor to Buensod-Stacey, Incorporated, New York, N. Y., a corporation of Delaware

Application May 5, 1955, Serial No. 506,160

4 Claims. (Cl. 98—40)

This invention relates to a device for controlling velocity and direction of the discharge of air to a zone or area in air conditioning systems, such discharge being quiet.

In air conditioning systems and the like, mixed air or air is fed into a room or zone from a duct or distributing unit through an aperture in said duct or unit. Normally, there may be a plurality of such apertures in ducts or units in various parts of the room so that it is desirable to control direction and velocity from each aperture into the room for proper distribution and prevention of undesirable drafts. In some instances, these apertures may be elongated in direction of flow so that the air should flow into the room throughout the length of the aperture.

One of the objects of the invention is to provide a simple means for controlling direction and velocity of air flowing into a room.

Another object is to provide an arrangement having an elongated aperture wherein air is distributed to the room throughout the length of the aperture and is controlled as to direction and volume therefrom.

A still further object of the invention is to provide an arrangement for discharging air into a room wherein the air is discharged at high velocity yet the operation is quiet.

In one aspect of the invention, the duct or distributing unit may be provided at appropriate places with elongated slots or apertures for feeding air into the zone. Each of these slots has a pair of pivoted blades or louvers extending along the slot and having surfaces movable toward and away from each other in such a manner as to control both direction and volume of air from said slot. The oppositely facing surfaces of the blades where the air enters therebetween preferably are convex so as to cooperate with each other in directing air flow therethrough, the passage in effect comprising a nozzle with a rounded streamline entrance. Such permits high velocity of discharge with a minimum of noise. A cam means can be located to contact each blade or means attached thereto so as to adjustably position said blades relative to each other as to width of opening and direction of air flow through the aperture or slot.

In a further aspect of the invention, a perforated plate, which can be concave in cross section, can be located along said slot in the path of the air flowing to said blades. It may be concave or have other shapes. Such will tend to cause air flowing along said duct to enter said zone throughout the length of the slot in the desired direction and manner.

Other advantages, objects and features of the invention will become apparent from the following description and drawings which are merely exemplary.

In the drawings:

Fig. 1 is a broken plan view of one form of the invention, the louvers or blades being in open position;

Fig. 2 is a fragmentary elevation of the left end of Fig. 1, the view being partly in section;

Fig. 3 is a section taken along the line 3—3 of Fig. 2;

2

Fig. 4 is a view similar to Fig. 3, with the control blades in a different relationship;

Fig. 5 is similar to Fig. 4 but illustrating a still different adjustment of the control blades;

Fig. 6 is a view partially in section, of a distributing unit in which the control louver or damper means is at the top, and the inlets for the warm and cold air to the unit are at the bottom;

Fig. 7 is a perspective view of one manner in which the outlet means can be used in a duct; and

Fig. 8 is another manner in which the outlet means can be arranged for controlling flow of air from a duct.

The arrangement described can be used in the outlet of a distributing unit wherein hot and cold air is mixed or can be used for distributing air from a duct. As an example, outlet control means generally shown at 9 (Fig. 6) can be located at the top of distributing unit 10, said distributing unit receiving air from cold air duct 11 and warm air duct 12. The air can be mixed and controlled in said unit as shown, for example, in Patent No. 2,690,983:

The wall of the distributing unit or duct may have an aperture or slot 13 for receiving control member frame 14 in which can be pivotally mounted longitudinally extending louvers or blades 15 and 16. Blade 15 is pivotally mounted on suitable pins or bearings at each end at 17 in frame 14 so as to be rotatable along its longitudinal axis about the pivots. Blade 16 is pivotally mounted in a similar manner at 18 and is independently movable with respect to blade 15. As can be seen in Figs. 3, 4 and 5, the blades have convex faces 20, 21 facing each other where the air enters therebetween so as to guide air passing through the control arrangement.

In order to adjust the position of the blades 15 and 16 relative to each other, cam means 22 and 23 may be provided. Cam means 22 is seen at the left hand end of the opening (Fig. 1) and is arranged to contact blade 15 as can be seen in Figs. 3 to 5. Cam means 22 may be mounted on post 24 and screw 25 can be loosened or turned so as to permit turning of cam 22. Spring 26 is fastened to frame 14 at 27, the other end 28 thereof being arranged to urge blade 15 in a clockwise direction (Fig. 3) against cam 22. Blade 16 is arranged in a manner similar to blade 15 with spring 29 urging the blade in a counter clockwise direction (Fig. 3) and against cam 23 at the right hand end of the aperture (Fig. 1). It should be apparent that both of the cams can be located at one end if desired although it is preferable to have one at each end, as illustrated. If cam 23 were located at the same end as cam 22 it would have the position seen in dotted lines 23A, Fig. 3. Upper lip or flanges 30, 31 of blades 15, 16 respectively can cooperate with flexible sealing strips 32, such as felt or the like, so as to close the upper portion of the outlet at this location and permit movement of the blades relative to each other and frame 14.

When the cams are arranged to adjust the blades as illustrated in Fig. 3, air will be directed upwardly and in a direction substantially perpendicular to the face of the unit or frame as shown by the arrows. In Fig. 4, cam 22 has not been turned as far as in Fig. 3 so that blade 15 is in a position which is clockwise displaced relative to its position in Fig. 3. Cam 23 (as illustrated by 23A) controlling blade 16 has been turned further than that in Fig. 3 so that the passage between blades 15 and 16 is such as to direct the air toward the right in Fig. 4 as compared with Fig. 3. In Fig. 5, each of the cams has been turned further than illustrated in Figs. 3 and 4 so that the opening between blades 15 and 16 has been increased. Cam 23 has been moved slightly more relative to the perpendicular face of the unit than cam 22 so that the air is

directed slightly to the right in Fig. 5 but not as much to the right as in Fig. 4. Similarly, the cams can be adjusted so that their axes coincide with the perpendicular to the face of the outlet so as to permit the upper portions of the blades to come substantially together and thus cut off flow of air.

The slot in a wall of the duct or unit may have a flexible gasket of rubber or the like around its edge as seen at 34 in Fig. 3, the inner edge thereof contacting the walls of frame 14 to provide a seal. In the form shown in Figs. 3 to 5, an ornamental or other wall 35 is engaged by the lips 36 of the frame, bolts or holding means 37 being provided for removably holding the unit in place. If the ornamental covering 35 is omitted, lips 36 will contact the gasket member 34 directly.

When the outlet control means is to be used in a duct wherein the aperture is elongated in the direction of flow of air in the duct such as seen in Fig. 7, the longitudinally extending perforated plate 33 (seen for example in Fig. 3) can be employed to cause air to flow through the aperture along substantially its entire length. As air passes along the plate, it can be theorized that a turbulence will be set up due to its passage over the apertures in such a manner as to tend to direct the air through the outlet opening along its entire length. If desired, two or more of the outlet controls can be employed side by side as illustrated in Fig. 8. The perforated plate also can be used when the outlet control is used in conjunction with the distributing box illustrated in Fig. 6.

The present device discharges the air into the zone at a higher than normal velocity yet is quiet in operation, the direction and velocity of discharge being readily adjustable. Also, the relatively long and narrow slot provides an air stream which does not carry as far nor does it provide the potentialities for creating drafts that a lower velocity outlet with lower aspect ratio or ratio of width to length.

It should be apparent that details of construction can be varied without departing from the spirit of the invention except as set forth in the appended claims.

What is claimed is:

1. In an air control device for the outlet of an air conditioning system distributing device, the combination including an outlet slot, a pair of cooperating air control blades having oppositely facing convex entrance faces providing a rounded nozzle-like entrance and controlling velocity and direction of air from said slot, pivot means for said blades, operating cams for each of said blades, each of said cams being independently rotatable to adjust the distance between said blades and the direction of said blades relative to said slot, and yieldable means holding each of said blades against its respective cam means.
2. In an air control device for an elongated aperture outlet of an air conditioning system distributing device,

4
the combination including a frame insertable in said aperture outlet, a pair of cooperating air control blades having facing convex entrance faces controlling air through said aperture outlet, pivot means in said frame for said blades, said pivot means being intermediate the edges of their respective blades, rotatable cam means on said frame for each of said blades, said cam means being rotatable to adjust the distance between said blades and the direction of said blades relative to said slot, and yieldable means holding each of said blades against its respective cam means.

3. In an air control device for an elongated outlet aperture of an air conditioning system distributing device, the combination including a frame mountable in said aperture, a pair of cooperating air control blades having convex entrance faces, said blades being pivotally mounted in said frame controlling direction and velocity from said aperture, cam means for each of said blades, said cam means being movable to adjust the distance between said blades and the direction of said blades relative to said aperture, a perforated plate located along said frame at the inlet to said blades to distribute air substantially evenly through said blades along said aperture, and yieldable means holding each of said blades against its respective cam means.

- 25

4. In an air control device for an elongated aperture outlet of an air conditioning system distributing device, the combination including a frame insertable in said aperture outlet, a pair of cooperating air control blades having facing convex entrance faces controlling air through said aperture outlet, said blades having lip means spaced from said convex faces extending toward the edges of said aperture, sealing means engaging said edges of said aperture and said lip means so as to prevent the flow of air therebetween, pivot means in said frame for said blades, cam means on said frame for each of said blades, said cam means being movable to adjust the distance between said blades and the direction of said blades relative to said slot, and yieldable means holding each of said blades against its respective cam means.
